(57) **CLAIM**

The ornamental design for a folding squat rack, as shown and described.

DESCRIPTION

FIG. 1 is a perspective view of the folding squat rack, showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the area labelled 9 in FIG. 1;

FIG. 10 is an enlarged view of the area labelled 10 in FIG. 1;

FIG. 11 is an enlarged view of the area labelled 11 in FIG. 1;

FIG. 12 is an enlarged view of the area labelled 12 in FIG. 1;

FIG. 13 is an enlarged view of the area labelled 13 in FIG. 2;

FIG. 14 is an enlarged view of the area labelled 14 in FIG. 2;

FIG. 15 is an enlarged view of the area labelled 15 in FIG. 2; and,

FIG. 16 is a perspective view of the folding squat rack in an alternate configuration.
